UNITED STATES PATENT OFFICE.

CHARLES DUDLEY, OF LINWOOD, NEW JERSEY.

TUBE-EXPANDER.

SPECIFICATION forming part of Letters Patent No. 333,206, dated December 29, 1885.

Application filed June 29, 1885. Serial No. 170,081. (No model.)

To all whom it may concern:

Be it known that I, CHARLES DUDLEY, a subject of the Queen of Great Britain, residing at Linwood, in the county of Atlantic and State of New Jersey, have invented certain new and useful Improvements in Adjustable Tube-Expanders, of which the following is a specification, reference being had therein to the accompanying drawings.

10 This invention has reference to that class of tube-expanders in which a tapering mandrel or spindle is used in conjunction with rollers placed within the tube to be expanded; and the invention consists in the construction of a 15 suitable frame-work in which the rollers are secured; also, in the construction of the rollers that will admit the same to freely adjust themselves within the tube and bear proper relationship to the tapering mandrel which operates them, and in the arrangement of parts by 20 which the same can be quickly removed and replaced within the frame-work.

I will proceed to describe the construction and operation of my device, reference being had to the accompanying drawings, in which—

25 Figure 1 is a side view showing all of the parts in operative position. Fig. 2 is a front view of the head or cap plate, and showing clearly the positions of the bolts which pass 30 through it to connect with the circular rim within the tube. Fig. 3 is a view of the opposite end of the expander, showing plainly the circular rim again and illustrating the positions occupied by the rolls and connecting-bolts. Fig. 4 is a section upon the line $\alpha\alpha$ of 35 Fig. 3, showing the peculiar construction of the rolls and the manner of holding them. Fig. 5 is a rear view of the cap-plate, showing the form and also the position occupied by the 40 radial slots in which the gudgeons of the rolls play.

Similar letters refer to like parts in the several views.

45 A tapering mandrel, D, passes through a hole, b' , in the cap-plate B and circular rim-plate F, thus separating the rolls C and causing the latter to adjust themselves along the inclined face of the tapering mandrel where the rolls are of the larger diameter and bear 50 upon the inclined face of the mandrel D. Bolts L, firmly secured in the circular rim-plate F, connect the latter with the cap-plate B, and

have flaring shoulders l , which butt against the rear walls of the inner plate, B', forming a portion of the cap. The pressure-rolls C are 55 each for about one-half their length from the rear end somewhat larger in diameter than the balance of said rolls, and at their rear ends are countersunk for a short depth sufficiently to form a rim, c' , within which plays 60 a pin, N, firmly secured in the circular rim-plate F. Gudgeons c , formed integral with rolls C, are free to move in radial slots b in the rear plate, B', of the cap, and thus the pressure-rolls are free to move and adjust themselves to the face of the incline of the tapering mandrel D. A collar or sleeve, E, of an outer diametric measurement equal to the front cap-plate, B, receives a bearing against the rear walls of the main cap-plate B, and 70 serves to span any projecting portion of tube that may extend beyond the tube-plate.

In operating this device it is simply necessary to introduce in the tube a suitable size expander, and in which the circular rim-plate 75 F will snugly fit the said tube to be acted upon, and then placing the tapering mandrel therein until the same will expand the rolls C to such an extent that they will impinge the inner walls of the tube at the proper point, then by 80 striking the mandrel a sufficiently light blow upon the end extending out of the tube as will cause the expander to so firmly bear against the inside of the tube that will necessitate the revolving of the tapering mandrel 85 by means of a wrench in the usual manner of devices, and thus by repeating the operation of driving in the tapering mandrel D, as explained, and revolving it, as described, will cause the tube to expand to the proper amount. 90

By the arrangement of parts in an expander for tubes as I have described, a single size may be utilized in a number of tubes of different diameters, for by loosening the connecting-bolts the pressure-rolls can be readily 95 removed, and smaller or larger ones, as the case may require, inserted.

Having thus described my invention, I claim the following:

1. In combination, tapering mandrel D, 100 rolls C, constructed substantially as described, having integrally-formed gudgeons c at one end and the opposite end countersunk, cap-plate B, formed in two parts and provided with

radial slots *b*, pins *N*, plate *F*, and the connecting-bolts *L*, as set forth.

2. In combination, rolls *C*, constructed as described, having gudgeons *c* at one end and the 5 opposite end countersunk, cap-plate *B*, formed of two plates and having radial slots *b*, connecting-bolts *L*, with flaring shoulders, and circular rim-plate *F*, having retaining-pins *N*, as described, and for the purpose set forth.
- 10 3. In combination, the cap-plate *B*, constructed as described, circular rim-plate *F*,

having retaining-pins *N*, connecting-bolts *L*, having flaring shoulders *l*, and the rolls *C*, having countersink *c'*, for the purposes specified.

15

In testimony whereof I affix my signature in presence of two witnesses.

CHARLES DUDLEY.
